ATTORNEYS,

UNITED STATES PATENT OFFICE.

WARREN COLE, JR., OF KNOXVILLE, TENNESSEE.

CANOPY.

SPECIFICATION forming part of Letters Patent No. 513,984, dated February 6, 1894.

Application filed February 10, 1893. Serial No. 461,758. (No model.)

To all whom it may concern:

Be it known that I, WARREN COLE, Jr., a citizen of the United States, residing at Knoxville, in the county of Knox and State of Tennessee, have invented certain new and useful Improvements in Canopies; and I do declare the following to be a full, clear, and exact description of the invention, such as will enable others skilled in the art to which it appertains

10 to make and use the same, reference being had to the accompanying drawings, and to the letters of reference marked thereon, which form a part of this specification.

My invention relates to an improvement 15 in canopies for beds, couches and like furniture, and it has particular reference to that class which is arranged to fold or swing from over the bed, or couch, and out of the way, when not in use.

20 It has for its object to produce an arrangement which can be easily applied to an ordinary bedstead and adjusted to the proper width and length, and one which can be more readily thrown back when not in use.

25 To this end it consists, generally stated, of a frame constructed preferably of metal, and arranged to automatically swing or fold back out of the way upon having its free end released. It also consists of certain details 30 of construction and arrangement or combination of parts which will be fully described hereinafter and finally embodied in the claims.

Referring to the accompanying drawings, 35 which show an arrangement having the essential elements of my invention, Figure 1, represents a perspective view of a bed supplied with my improvements, and Fig. 2, a detail view showing more plainly the bracket 40 or support by which the frame is secured to the bed.

The reference letter *a*, indicates a bed of ordinary or any preferred construction, having as usual the head and foot-boards *b*, *b'*. 45 To the head-board *b* are secured my improvements. This is done by means of the brackets *c*. These are formed of metal, preferably of cast steel, and provided with arms *d*, and *d'*. Arm *d*, is secured by means of screws or 50 bolts, passing through openings therein, to the head-board of the bed, as before stated, in such a position that the arm *d'*, will ex-

tend horizontally and parallel with the vertical sides of the head-board. Two of these brackets are provided for the canopy, each 55 being used to support one of the side portions of the frame, as will more fully appear hereinafter. The arm *d'*, of the bracket *c*, is formed in the shape of an angle iron in cross-section and arranged with its respective 60 sides, horizontal and vertical. In the horizontal portion or side of the arm *d'*, is formed a series of openings or recesses *e*, extending entirely through it; the vertical portion having its upper edge formed with a series of 65 notches or indentations *e'*, conforming in number and alignment to the holes *e*, in the horizontal portion.

The frame of my invention consists of the curved metallic side bars *f*, *f'* joined at their 70 outer ends by means of a cross-bar or connecting piece *g*, secured thereto in any preferred manner. The inner ends of the bars *f*, and *f'*, are each curved downwardly and formed so that a spiral or helical spring *g'*, 75 of several coils is formed. The extreme inner ends of the bars *f*, and *f'*, are formed or bent at right angles to the remaining portion and adapted to fit into the holes *e*, in the horizontal portion of the arm *d*. From thence it 80 extends up and over the edge of the vertical portion, it being held securely and prevented from swinging laterally by means of the notches *e'*, into one of which it fits. The helical spring *g'*, is constructed with a tendency 85 to throw the arms *f*, and *f'*, into a vertical position, such being the normal condition of the arm.

By means of the opening *e* in the brackets *c*, the arms *f*, *f'* may be moved toward or 90 from each other to compensate for the difference between the size of the canopy netting and the width of the bed. Thus if the netting was one size and the bed wider than the netting, it would be necessary to move the 95 arms toward each other so that they would conform to the width of the netting. In practice this condition of affairs will very often, if not always, occur, for the netting on the market at present is adapted to be used in 100 connection with the usual hanging supports which are always smaller or narrower than the bed.

Secured to the frame of the canopy is the

netting *h*, which may be of any suitable quality or kind. This netting is arranged to hang loosely from the frame and when the canopy is in the position shown in Fig. 1, to drop or hang from the frame and cover the bed as is usual in this class of inventions. Connected to the outer ends of bars *f*, and *f'*, are the cords *i*, preferably two in number, and joined at their lower ends to a tassel, or 5 an ornamental handle *i'*. These cords are arranged to be connected at their lower ends to the button or thumb screw *j*, fastened to the foot-board of the bed. By this means 10 the canopy frame is held in a horizontal position, against the tendency of the spring *g'*. 15 When it is desired to use the canopy in connection with a bed, it is secured in position, as previously explained and the arms *f*, and *f'*, drawn down to a substantially horizontal or overhanging position, and secured 20 in such by means of the cords *i*, and button *j*, the netting *h*, being allowed to hang from the frame and envelop the bed, as previously explained. To fold the canopy back and out 25 of the way, as will be desirous when it is not preferred to use the canopy, all that will be necessary is to unfasten or release the cords *i*, whereupon the frame and its attachment will, of its tendency, swing back to a vertical position, 30 thereby disposing of the netting. This operation is shown in Fig. 1.

The function of the resilient arms *f*, *f'* is twofold: First. By means of their peculiar properties when the ends are secured by the 35 cords *i*, they will describe a curve or arch over the body of the bed, thus permitting the arms to be arranged so low on the headboard *a* that when swung to a vertical position they will not be affected by the ceiling, and yet 40 render it possible for a person to get in and out of the bed without striking the arms or canopy netting supported by them. This is shown in dotted and full lines in Fig. 1. Second. If the ceiling should be so low that it 45 would be impossible to prevent its contact with the arms when raised, all harm which would otherwise result from such contact, is avoided by the capability of the arms to bend and conform themselves to the ceiling, and 50 not strike them so violently as to harm the ceiling or themselves.

Having thus described my invention, what I claim as new, and desire to secure by Letters Patent, is—

55 1. In a canopy frame, the combination of an arm having one of its ends formed into a coiled or helical spring which spring is adapted to be secured to the bed, the said spring giving the arm a tendency to assume a vertical position, and means for holding the arm in a horizontal position against the tendency of the spring, substantially as described.

60 2. In a canopy frame, the combination of a bracket adapted to be secured to the bed, a portion of which bracket extends in a direction at right angles to the longitudinal posi-

tion of the bed and is provided with a series of openings extending in a line therewith, a spring arm secured to the bracket by means of the openings therein and having by reason 70 of its inherent spring properties a tendency to assume a vertical position, and means for holding the arm in a horizontal position against its spring tendency, substantially as described.

75 3. In a canopy frame, the combination of a bracket adapted to be secured to the bed, an arm having one of its ends formed into a spring and thereat secured to the bracket, said spring giving the arm a tendency to assume a vertical position, and means for holding the arm in a horizontal position against the tendency of the spring, substantially as described.

80 4. In a canopy for beds, the combination of a bracket adapted to be secured to the bed, an arm having its end formed into a coiled or helical spring and thereat secured to the bracket, said spring giving the arm a tendency to assume a vertical position, means 90 for holding the arm in a horizontal position against the tendency of the coiled or helical spring, and netting secured to the arm and arranged to envelop the bed, substantially as described.

85 5. In a canopy frame, the combination of a bracket adapted to be secured to the bed, a portion of which bracket extends in a direction at right angles to the longitudinal position of the bed and is provided with a series 90 of openings extending in a line with the said portion of the bracket, an arm having one formed into a spring and thereat secured to the bracket by means of the openings therein, said spring giving the arm a tendency to assume a vertical position against the tendency of the spring, and means for holding the arm in a horizontal position, substantially as described.

95 6. In a canopy frame, the combination of a bracket adapted to be secured to the bed, a portion of which bracket extends in a direction at right angles to the longitudinal position of the bed and is provided with a series 100 of openings extending in a line with the said portion of the bracket, an arm having one end formed into a coiled or helical spring and thereat secured to the bracket by means of the openings therein, said coiled or helical spring giving the arm a tendency to assume 105 a vertical position, and means for holding the arm in a horizontal position against the tendency of the spring, substantially as set forth and described.

110 7. In a canopy for beds, couches and like 115 furniture, the combination of a pair of brackets secured to the head or foot-board thereof, an arm on each of said brackets, and having formed therein a series of corresponding, holes and notches, a pair of bars or arms, 120 having their inner extremities formed into a helical spring and secured to the arms of said

bracket through the medium of the holes and notches, a cross-bar connecting the outer ends of the said bars, netting secured to the bars and cross-bar and arranged to envelop the

5 bed, cords depending from the outer ends of the said bars and a button fixed to the foot-board of the bed, by means of which the cords are fastened to the foot-board and the frame of the canopy held in a horizontal po-

sition against the tendency of the said helical spring.

In testimony whereof I affix my signature in presence of two witnesses.
